Francis J. Fracker of Boston Mass.

Assignor to

The Duckor Manufacturing Company of the same place.

Letters Patent No. 2369. Date, July 24, 1866.

Design for "Pendant light."

The schedule referred to in the aforesaid Letters Patent and making part of the same,

to all whom it may concern:

Be it known that I, F. J. Fracker of Boston, in the County of Suffolk and State of Massachusetts have originated and produced a new Design for a "Pendant light," of which the following is a full and clear description, reference being had to the accompanying drawing making part of this Specification.

In the Design represented by the drawing, is a hanger frame made of vertical pieces a, a, and the top and bottom pieces b, c, the bottom piece bearing mounted upon it, a basket-shaped holder d, for containing or supporting the lamp e.

I claim the Design for a "Pendant light," as shown and described

Witnessed,

J. B. Crosby

S. Gould.

Francis J. Fracker.
